UNITED STATES PATENT OFFICE.

MURRAY T. BERMAN, OF NEW YORK, N. Y.

AMUSEMENT APPARATUS.

Application filed March 14, 1923. Serial No. 625,001.

To all whom it may concern:

Be it known that I, MURRAY T. BERMAN, a citizen of the United States, residing at New York, in the county of New York and State of New York, have invented new and useful Improvements in Amusement Apparatus, of which the following is a specification.

This invention relates to amusement apparatus.

Some of the objects of the present invention are: an apparatus with which persons may control and direct balls as they roll from a starting point to a finishing point or goal, in competition with each other, there being one ball under the control and being directed by each person; an apparatus as just featured in which each of the balls has to travel in a circuitous path to get to the goal; an apparatus as just featured which includes ball-race units with means common to all of said ball-race units for releasing the balls employed, means common to all of said ball-race units for discharging the balls from the race-ways, and means for manipulating the balls subsequent to their release and until one has reached the goal, the latter means each being under control of one person; and with these and other objects in view the invention resides in the combination, relative disposition, construction, and operation of the parts hereinafter fully described and illustrated in the accompanying drawings, in which:

Figure 1 is a plan view.

Figure 2 is a side elevation.

Figure 3 is a sectional view taken on the line 3—3, Figure 1.

Figure 4 is a diagrammatic view illustrating the ball-discharging means.

Figure 5 is a diagrammatic view illustrating the ball-releasing means.

Figure 6 is a perspective view of a pair of the ball-propellers.

The apparatus of the present invention, generally, comprises ball-race units 10 supported at an inclination by a supporting structure 11 including a counter 12, ball-releasing means 13, ball-manipulating or controlling and directing means 14, and ball-discharging means 15.

Each ball-race unit 10 comprises a frame 16 having side rails 17 and end rails 18 to define a substantially rectangular space which is subdivided by members 19 into regions or compartments, there being a

starting compartment 20, intermediate compartments 21, and a finishing compartment 22. The members 19 are preferably glass and are arranged in spaced relationship end to end and side to side thus defining the compartments or regions mentioned and defining passages 23 also which in fact allows a ball to travel from the compartment 20 to the compartment 22. The members 19 are of such lengths and so arranged as to require that a ball travel in a circuitous path to get from the compartment 20 to the compartment 22 and also act as obstacles as the ball rolls in its downward course. The compartment 20 has an entrance 24 at which it is temporarily confined and through which it passes to the starting compartment 20 when released. The frame 16 has a bottom 25 having openings therein which occur in each of the compartments for a reason to appear.

The ball-releasing means 13 is common to all of the ball-race units 10, and in the present instance comprises slides or doors 30, there being one at each of the entrances 24, and these doors 30 are connected to rocking levers 31 connected to a rock-shaft 32 mounted in suitable bearings 33. A hand-lever 34 connected to the rock-shaft serves for the rocking of the rock-shaft 32 and the raising and lowering of the doors 30 in unison.

Each ball-manipulating means 14 comprises oscillatory ball-propellers 40 and an operating device 41 for effecting the oscillation of the ball-propellers 40. The device 41 comprises a rock-shaft 42 mounted in suitable bearings 43 beneath its associated ball-race unit 10 longitudinally and centrally thereof. A pair of opposed ball-propellers 40 are employed in conjunction with each of the compartments of the associated unit 10, and the said ball-propellers are carried by a bracket or support 44 attached in any suitable manner to the rock-shaft 42. Portions of the ball-propellers extend through openings in the side rails 17. A manipulating handle 45 is connected to one end of the rock-shaft 42 and the grip 46 of said handle is disposed in juxtaposition to the top of the counter 12 by virtue of an opening in the said top which opening has buffers 47 at the ends thereof to limit and cushion the handle 45 in its movement. It should now be manifest that upon manipulation of the handle 45 the ball-propellers

will move or oscillate and thus will propel a ball when contacting the same to either the left or the right.

The ball-discharging means 15 is common to all of the ball-race units 10, and in the present instance comprises hingedly mounted doors 50 and mechanism 51 for swinging said doors 50. A door 50 is arranged in the opening of the bottom 25 of each unit 10 and the doors of each unit are connected to a rod 52 to which is attached a strap iron 53 with a recess 54. A rock-shaft 55 is employed and is mounted in suitable bearings. A lever 56 is carried by the rock-shaft 55 and the free end of the lever is bifurcated and carries rollers 57 between which the strap iron 53 extends. A hand lever 58 is employed and is connected to the rock-shaft through the intervention of a lever 59 pivoted as at 60, an arm 61 connected to the rock-shaft 55 and a rod 62 which connects the lever 59 and the arm 61. It should now be manifest that upon movement of the hand lever 58 the doors 50 may be raised and lowered at will in unison. When raised the doors have their upper surfaces flush with the upper surfaces of the bottom 25 of each of the units 10 and with the latter serve as a way over which the balls 63 roll. Suitable stops 64 are employed to limit the downward movement of each door 50.

It is to be noted that the hand-lever 34 of the ball-releasing means is at the rear of the apparatus, whereas, the hand-lever 58 of the ball-discharging means is at the front of the apparatus.

In practice the frame 16 will have a glass cover 70 which not only serves in the confinement of the ball of each unit but also 40 allows the participant to observe the progress of the ball as it travels toward the goal.

In the operation of the apparatus the balls are released by an attendant in the manipulation of the hand-lever 34; the balls 45 passing through the entrances 24 to the starting compartments 20. The participants in the manipulation of the handles 45 control and direct the balls individually to pass through the passages 23 until one of the 50 participants is successful in directing his or her ball as the case may be to the finishing compartment or goal who is then and thereby declared to be the winner. Further manipulation of the handle then ceases and 55 the ball-discharging means is operated whereupon all of the balls irrespective of what compartments they may be in will be discharged by virtue of the lowered doors 50 to a suitable chute or run-way provided 60 to return the balls to the rear of the apparatus.

It is to be understood that any preferred number of units 10 may be employed and it is also to be understood that any and all 65 changes, alterations and modifications with-

in the scope of the claims hereunto appended may be resorted to whenever it is deemed necessary or desirable.

What I claim is:

1. An amusement apparatus comprising 70 balls, inclined ball-races over each of which one of said balls rolls, ball-releasing means for starting the downward roll of all of said balls over said ball-races respectively, ball-manipulating means for manipulating each 75 of said balls after being released by said releasing means as it rolls over its ball-race, and ball-discharging means for discharging all of said balls from said ball-races, when one of the balls has reached the limit of its 80 travel over the ball-race.

2. An amusement apparatus comprising 85 balls, inclined ball-races over each of which one of said balls rolls, each of said ball-races including obstacles spaced end to end and side to side to define compartments and 90 passages through which latter the ball passes when properly manipulated, ball releasing means for starting the downward roll of all of the balls over said ball-races respectively, ball-manipulating means for manipulating each of said balls as it rolls over its ball-race, after being released by said ball 95 releasing means and ball-discharging means for discharging all of said balls from said ball-races, when one of the balls of the ball-races has passed all of said obstacles.

3. An amusement apparatus comprising 100 balls, inclined ball-races over each of which one of said balls rolls, ball-releasing means for starting the downward roll of all of the balls over said ball-races respectively, said ball-releasing means including doors movable in unison; ball-manipulating means for manipulating each of said balls as it rolls 105 over its ball-race after being released by said ball releasing means, and ball-discharging means for discharging all of said balls from said ball-races when one of the balls has reached the end of its respective ball-race. 110

4. An amusement apparatus comprising 115 balls, inclined ball-races over each of which one of said balls rolls, each of said ball-races having a starting compartment with an entrance through which the ball passes in its downward roll, ball-releasing means for starting the downward roll of all of the balls over said ball-races, said ball-releasing means including doors movable in unison, one door being arranged at entrance of each starting compartment mentioned; ball-manipulating means for manipulating each of said balls as it rolls over its ball-race, after having been released by said ball releasing 120 means and ball-discharging means for discharging all of said balls from said ball-races when one of the balls has reached the end of its respective ball-race. 125

5. An amusement apparatus comprising 130

5 balls, inclined ball-races over each of which one of said balls rolls, ball-releasing means for starting the downward roll of all of the balls over said ball-races respectively, ball-
manipulating means for manipulating each of said balls as it rolls over its ball-race, after having been released by said ball releasing means said ball-manipulating means including oscillatory ball-propellers; and
10 ball-discharging means for discharging all of said balls from said ball-races when one of the balls has reached the end of its respective ball-race.

6. An amusement apparatus comprising
15 balls, inclined ball-races over each of which one of said balls rolls from a starting point to a goal, ball-releasing means for starting the downward roll of all of the balls over said ball-races respectively, ball-ma-
nipulating means for manipulating each of said balls as it rolls over its ball-race, after having been released by said ball releasing means, said ball-manipulating means including oscillatory ball-propellers and an
20 operating handle connected to each of said oscillatory ball-propellers; and ball-dis-
charging means for discharging all of said balls from said ball-races when one of the balls has reached the end of its respective ball-race.

7. An amusement apparatus comprising
balls, inclined ball-races over each of which one of said balls rolls from a starting point to a goal, ball releasing means for start-
35 ing the downward roll of all of the balls over said ball-races respectively, ball-ma-
nipulating means for manipulating each of said balls as it rolls over its ball-race, after being released by said releasing means and
40 ball-discharging means for discharging all of said balls from said ball-races, when one of the balls has reached its goal, said ball-discharging means including hingedly mounted doors movable in unison.

45 8. An amusement apparatus comprising
balls, inclined ball-races over each of which one of said balls rolls from a starting point to a goal, ball-releasing means for start-
50 ing the downward roll of all of the balls over said ball-races respectively, ball-manipulat-
ing means for manipulating each of said balls as it rolls over its ball-race, after being released by said releasing means and
55 ball-discharging means for discharging all of said balls from said ball-races, when one of the balls has reached its goal, each of said ball-races embodying intercommunicating compartments, said ball-discharging means comprising hingedly connected doors and
60 mechanism for effecting the movement of said doors in unison and one of said doors being arranged so as to constitute the bottom of each of said compartments.

9. An amusement apparatus comprising

65 balls, inclined ball-races over each of which one of said balls rolls from a starting point to a goal, each of said ball-races comprising obstacles arranged transversely with respect to the surface on which the ball rolls, the obstacles being disposed in spaced re-
70 lationship end to end and side to side to define compartments and ball-passages, the latter being out of alinement, and there being a starting compartment and a finishing compartment or goal; ball-releasing means 75 for starting the downward roll of all of the balls over said ball-races respectively, said ball-releasing means comprising doors and mechanism for effecting the movement of said doors in unison, one of said doors being arranged at the entrance to each of said starting compartments; ball-manipu-
80 lating means for manipulating each of said balls as its rolls over its ball-race, after the ball has been released by said ball re-
leasing means, said ball-manipulating means comprising oscillatory ball-propellers and a device having a handle for effecting the oscillatory movement of said ball-propellers, there being two ball-propellers disposed in 85 each of said compartments; and ball-dis-
charging means for discharging all of said balls from said ball-races, when one of the balls reaches its respective goal, said ball-
discharging means comprising hingedly mounted doors and mechanism for effecting the movement of said hingedly mounted doors in unison, and one of said hingedly mounted doors being arranged at the bottom of each of said compartments. 95

10. In an amusement apparatus with which participants control and direct rolling balls as they roll from a starting point to a goal, surfaces over each of which a ball rolls, obstacles over each of said surfaces and arranged to define a circuitous passage through which the ball may roll, oscillatory ball-propellers arranged in opposed pairs, and operating means for effecting the oscillation of the ball-propellers, 110 during the passage of the balls over said surfaces there being ball-propellers and operating means associated with each of said surfaces and the obstacles thereon for directing the ball through the circuitous pas- 115 sage.

11. In an amusement apparatus with which participants control and direct rolling balls as they roll from a starting point toward a goal, ball-race units in each of 120 which one ball rolls when released, means for releasing all of the balls simultaneously, each ball-race unit including means for controlling and directing the ball as it rolls over the ball-race units toward the goal. 125

In testimony whereof I hereby affix my signature.

MURRAY T. BERMAN.
